(57) **CLAIM**

The ornamental design for a packaging container cap, substantially as shown and described.

DESCRIPTION

FIG. 1 is a front view of our new, original and ornamental design for a packaging container cap;

FIG. 2 is a left side view thereof;

FIG. 3 is a plan view thereof;

FIG. 4 is a bottom view thereof;

FIG. 5 is a cross sectional view thereof taken at line 5-5 of FIG. 1;

FIG. 6 is a cross sectional view thereof taken in the direction of line 6-6 of FIG. 1;

FIG. 7 is a cross sectional view thereof taken in the direction of line 7-7 of FIG. 2;

FIG. 8 is a cross sectional view thereof taken at line 8-8 of FIG. 7; and,

FIG. 9 is a cross sectional view thereof taken at line 9-9 of FIG. 7.

In the accompanying drawings, a rear view is identical to a front view and is omitted; and also right side view is identical to a left side view and is omitted.
